UNITED STATES PATENT OFFICE.

JOHN TAYLOR, OF CHICAGO, ILLINOIS.

BATTERY-PLATE PULLER.

Application filed July 20, 1925. Serial No. 44,936.

This invention relates to a battery plate puller and has for its primary object the construction of a plate puller that will more effectively engage the battery plates in a 5 manner to facilitate the pulling of the plates from the battery casing.

An object of the invention is the novel substantial manner in which the parts are so connected that when the handle is subjected 10 to a pulling operation the jaw elements will be rigidly forced into engagement with the plates.

A feature of my invention is the adjustability of the sets of jaws towards and away 15 from each other to compensate for different size plates.

With these and other objects in view, the invention will be better understood from the following description taken in connection 20 with the accompanying drawings, wherein:

Fig. 1 is a side elevation of my improved plate puller in applied position.

Fig. 2 is a front elevation partly in section. Fig. 3 is an enlarged sectional view 25 through the puller adjacent the jaw elements.

Fig. 4 is a sectional view on the line 4—4 of Fig. 3.

Again referring to the drawings illustrating one of the many constructions of my invention, the numerals 1 and 2 designate a double set of jaws each set having jaw elements 3 rigidly secured to the short arm 4 of a pair of pivoted levers 5. The long arms 6 of the levers are pivotally connected to the handle 7 by the links 8. It will be noted that the handle 7 which is of insulating material has arranged in each end pins 8' and 9 upon which are mounted the links. It will also be noted that the pin 9 is of increased length so that the links mounted thereon, besides having pivotal movement, may have longitudinal movement towards and away from the handle so that the distance between 45 the sets of links may be increased or decreased for compensating for the variation in the distance between the posts 10 of the

battery plates. Each jaw element 3 is provided with teeth 11 for increasing the effective engagement of the elements with the 50 posts 11.

From the foregoing description taken in connection with the accompanying drawings, it will be apparent that the post of the battery plate may be quickly and effectively 55 gripped and in proportion to the resistance of the plates in being removed, the effective grip between the jaw elements and the post is proportionally increased owing to the combination of the levers and the links. The 60 insulating handle 7 prevents short circuiting between the sets of jaws while at the same time providing an effective grip for the puller.

It is, of course, to be understood that the 65 jaw elements and various other parts may be connected in other relations than illustrated and therefore, I do not desire to be limited in any manner except as set forth in the claims hereunto appended.

Having thus described my invention, what 70 I claim is:

1. As a new article of manufacture, a battery plate puller comprising a handle of insulating material, two sets of pivoted jaw 75 members, links for each set of jaw members, a pin for pivotally connecting one set of links to one end of said handle and a second pin mounted in the other end of the handle pivotally supporting the other set of 80 links for relative movements and for longitudinal movements along the shank of the pin.

2. A battery plate puller comprising a handle, two sets of gripping jaws, means for 85 pivotally connecting one set of said gripping jaws to one end of said handle, a relatively long pin extending from the opposite end of said handle and the other set of gripping jaws being pivotally and slidably mounted 90 upon said pin.

In testimony whereof I affix my signature.

JOHN TAYLOR.
